ATTORNEY.

UNITED STATES PATENT OFFICE.

THOMAS TAYLOR, OF SAN FRANCISCO, CALIFORNIA.

DESIGN FOR A BROOM LOCK.

60,588.

Specification for Design.

Patented Mar. 7, 1922.

Application filed August 23, 1921. Serial No. 494,743. Term of patent 3½ years.

To all whom it may concern:

Be it known that I, THOMAS TAYLOR, a citizen of the United States, residing at the city and county of San Francisco, State of California, have invented a new, original, and ornamental Design for a Broom Lock, of which the following is a specification, reference being had to the accompanying drawing, forming part thereof.

Figure 1 is a side view of the broom lock showing my new design.

Figure 2 is a side view of my broom lock showing its position on the handle adjacent to the base of the broom.

I claim:

The ornamental design for a broom lock as shown.

THOMAS TAYLOR.
